US0D1031981S

(12) **United States Design Patent** (10) **Patent No.:** **US D1,031,981 S**
(45) **Date of Patent:** **** Jun. 18, 2024**

(54) **WIRELESS STETHOSCOPE**

(71) Applicant: **Quanta Computer Inc.**, Taoyuan (TW)

(72) Inventors: **Barry Lam**, Taoyuan (TW);
Chia-Yuan Chang, Taoyuan (TW);
Jung-Wen Chang, Taoyuan (TW);
Kao-Yu Hsu, Taoyuan (TW)

(73) Assignee: **QUANTA COMPUTER INC.**,
Taoyuan (TW)

(**) Term: **15 Years**

(21) Appl. No.: **29/812,032**

(22) Filed: **Oct. 19, 2021**

(30) **Foreign Application Priority Data**

Sep. 14, 2021 (TW) 110304934

(51) **LOC (14) Cl.** **24-02**

(52) **U.S. Cl.**

USPC **D24/134**

(57) **CLAIM**

The ornamental design for a wireless stethoscope, as shown and described.

DESCRIPTION

FIG. 1 is a front perspective view of a wireless stethoscope in accordance with our new and ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines show portions of the wireless stethoscope that form no part of the claimed design.

1 Claim, 7 Drawing Sheets
